FOUNTAIN SHAVING BRUSH

Peyton Rowan, Anniston, Ala.

Application February 19, 1942, Serial No. 431,548

6 Claims. (Cl. 15—138)

This invention relates to a fountain shaving brush, and has for its objects the provision of a device of the character designated which shall embody improved means for heating a soap and water mixture as it is fed to the brush; an improved feeding means for supplying the soap and water mixture to the brush; means for keeping the mixture and the bristles hot while in use; an improved pump element included in the feeding means; a combined feeding and warm massaging element in association with the brush; and a device which is simple of design and operation and easily manufactured.

Briefly, my invention comprises a shaving brush in which the handle portion is divided into two compartments, the outer of which, that is, the more remote from the brush, is adapted as a reservoir for holding a soap and water mixture, and the inner compartment houses a heating element. A feed tube extends from the outer compartment or reservoir through the inner to the brush and is surrounded in the inner compartment by the heating element, whereby the soap and water mixture is heated on its way to the brush. The end of the tube adjacent the brush is provided with a distributing head which also serves as a massaging element and which is heated by the heating element by conduction through the feed tube. In the reservoir is mounted a valve in the form of a plunger controlling the passage through the feed tube. Upon reciprocation, the plunger, in cooperation with lateral passages in the upper end of the feed tube, functions as a pump to force the soap and water mixture through the feed tube.

Apparatus embodying features of my invention is illustrated in the accompanying drawing forming a part of this application, in which

Fig. 1 is a longitudinal sectional view;

Fig. 2 is a plan view looking at the outer end of the brush handle;

Fig. 3 is a sectional view taken on the line III—III of Fig. 1;

Fig. 4 is a transverse sectional view drawn to an enlarged scale through the plunger stem and taken along the line IV—IV of Fig. 5;

Fig. 5 is a fragmentary sectional view of the upper end of the plunger stem;

Fig. 6 is a detail sectional view of the upper end of the feed tube and plunger taken along the line VI—VI of Fig. 7;

Fig. 7 is a sectional view taken along the line VII—VII of Fig. 6;

Fig. 8 is a sectional view taken along the line VIII—VIII of Fig. 1; and

Fig. 9 is a sectional view taken along the line IX—IX of Fig. 1.

Referring to the drawing, my improved fountain brush embodies a casing 10 having in its upper part, or part more remote from the brush, a reservoir 11 for a soap mixture, to which access is had for filling through an opening 12 provided with a pivotally mounted cover 13 which is adapted to be swung open to the dotted position shown in Fig. 2. Any suitable means may be employed to prevent the mixture in the reservoir 11 from leaking out around the cover 13 when the device is in use.

A metal feed tube 14 extends from the reservoir 11 down through the lower handle portion 16, which constitutes a heating chamber. The heating chamber 16 is separated from the reservoir 11 by the bottom 17 of the reservoir, which acts as a partition. The tube 14 has a central passage 18 which extends from the reservoir 11 through the heating chamber 16 to the lower end of the brush, where a metal head 19 is screwed on to the tube 14 and which pulls the reservoir 11 down against the shoulder 15 on the casing 10, and holds it in place. A brush holding element 21 surrounds the lower end of the tube 14, and is held in place by the metallic head 19. Bristles 22 are carried by the brush holding element 21, being secured thereto in any suitable manner.

As shown in the drawing, the metallic head 19 is rounded off and cupped at its extremity to provide a massaging element which, as shown, is positioned centrally of the brush. A plurality of passages 23 are provided in the head 19, which passages lead from the passage 18 in the tube 14 to supply the soap mixture to the bristles 22. Surrounding the tube 14 in the heating chamber 16 is an electric heating element 24, which is of limited heating capacity to avoid overheating of the device, and which has leads 25 mounted in a suitable casing 26 on the side of the brush handle, and terminating in a plug 27 adapted to be inserted in any suitable electric outlet.

The upper end of the tube 14 is bored out to form a cylinder 28 having lateral admission ports 29. The lower end of the cylinder 28 terminates in a conical valve seat 31 leading into the passage 18 of the tube 14. See Figs. 6 and 7. Fitting snugly in the cylinder 28, as shown in Figs. 1 and 7, is a plunger, or piston 32. The lower end of the plunger 32 is shaped to correspond to the lower end 31 of the cylinder 28, whereby when the plunger is in its lowermost position it acts as a valve to close off communication with the passage 18 in the tube 14. A plunger rod 33 is

secured to the upper end of the plunger and projects outwardly through the cover 34 of the reservoir 11. A spring 36 surrounding the rod 33 normally serves to hold the plunger down with the lower valve forming end on its seat 31 to prevent the escape of soap mixture.

The plunger 32 may be reciprocated by means of a lever 37 loosely connected to the upper end of the rod 33 and pivoted at 38 on the cover 34. The outer end of the lever 37 is provided with a thumb piece 30 whereby it may be pressed downwardly to raise the plunger, the spring 36 forcing the plunger downwardly when pressure is relieved. It will be seen that when the plunger 32 is raised, soap mixture enters the cylinder 28 through the ports 29, to be forced downwardly through the passage 18 when the plunger 32 moves downwardly.

In order that air may be admitted to the reservoir 11 when the plunger is being reciprocated, I provide the rod 33 near its upper end adjacent the cover 34 with a recess 41 which is normally beneath the cover, but which moves above the cover 34 on the upstroke of the plunger, and below the cover on the downstroke. A washer 42 surrounds the plunger 33 at the cover 34 to prevent leakage out of the reservoir 11. By the arrangement just described, a small amount of air is carried into the reservoir at each stroke of the plunger, which is sufficient to prevent a vacuum being formed in the reservoir 11 and to permit the plunger 32 to operate as a pump.

Preferably, the reservoir 11, tube 14, cylinder 28, and distributing head 19 are all made of metal and are surrounded by a casing 43 made from a suitable plastic material, such as the well known phenolic or urea resins. A suitable layer 44 of insulation preferably separates the outer casing 43 from the reservoir 11 and the heating elements 24 to prevent excess transfer of heat through the walls of the device.

From the foregoing it will be apparent that I have devised a fountain brush embodying an improved feeding means, an improved means for heating the mixture being supplied to the brush, and an improved distributing and massaging head for applying the mixture to the user's face.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. In a fountain shaving brush, a hollow handle divided by a transverse partition to provide a soap mixture reservoir remote from the brush and a heating chamber adjacent the brush, a feed tube extending from the reservoir through the heating chamber to the brush, heating means in the heating chamber surrounding the feed tube, and means on the end of the feed tube to distribute the soap mixture to the brush.

2. In a fountain shaving brush, a hollow handle a transverse partition in the handle dividing it into a soap mixture reservoir remote from the brush and a heating chamber adjacent the brush, a feed tube extending from the reservoir through

the heating chamber to the brush, heating means in the heating chamber surrounding the feed tube, a cylinder on the end of the feed tube in the reservoir and having lateral inlet ports, a valve seat in the end of the cylinder at the entrance to the feed tube, a reciprocable plunger fitting snugly in the cylinder for forcing soap mixture through the feed tube, and manually operable means to reciprocate the plunger.

3. In a fountain shaving brush, a hollow handle a transverse partition in the handle dividing it into a soap mixture reservoir remote from the brush and a heating chamber adjacent the brush, a feed tube extending from the reservoir through the heating chamber to the brush, heating means in the heating chamber surrounding the feed tube, a cylinder on the end of the feed tube in the reservoir and having lateral inlet ports, a valve seat in the end of the cylinder at the entrance to the feed tube, a reciprocable plunger fitting snugly in the cylinder for forcing soap mixture through the feed tube, manually operable means to reciprocate the plunger, and means to admit limited amounts of air to the reservoir at each stroke of the plunger.

4. In a fountain shaving brush, a hollow handle, a transverse partition in the handle dividing it into a soap mixture reservoir remote from the brush and a heating chamber adjacent the brush, heating means in the heating chamber, a feed tube extending from the reservoir through the heating chamber, a brush surrounding the end of the feed tube, means for forcing limited amounts of the soap mixture through the feed tube to the brush, and a distributing head secured to the end of the feed tube centrally of the brush and having laterally extending passages therein communicating with the feed tube, said distribution head terminating in a rounded cupped end adapted to massage the face and rub the lather formed by the soap mixture into the pores of the skin.

5. In a fountain shaving brush, a hollow handle, a transverse partition in the handle dividing it into a soap mixture reservoir remote from the brush and a heating chamber adjacent the brush, heating means in the heating chamber, a feed tube extending from the reservoir through the heating chamber, a brush surrounding the end of the feed tube, means for forcing limited amounts of the soap mixture through the feed tube to the brush, and a distributing head screwed on to the end of the feed tube and holding the brush in place thereon, said distributing head having lateral passages therein communicating with the feed tube.

6. In a fountain shaving brush, a hollow handle, a transverse partition in the handle dividing it into a soap mixture reservoir remote from the brush and a heating chamber adjacent the brush, heating means in the heating chamber, a feed tube extending from the reservoir through the heating chamber, a brush surrounding the end of the feed tube, means for forcing limited amounts of the soap mixture through the feed tube to the brush, a relatively hard distributing and massaging element screwed on to the outer end of the feed tube in a position to be heated by the heating element and serving to maintain the soap mixture hot as it is fed to the brush.

PEYTON ROWAN.
